(57) **CLAIM**

I claim the ornamental design for fiber feeding display glasses, as shown and described.

DESCRIPTION

FIG. 1 is a front perspective view of fiber feeding display glasses incorporating my new design;

FIG. 2 is a front view thereof;

FIG. 3 is a rear view thereof;

FIG. 4 is a right view thereof;

FIG. 5 is a left view thereof;

FIG. 6 is a bottom view thereof; and,

FIG. 7 is a top view thereof.

The broken line showing on the fiber feeding display glasses is included for the purpose of illustrating only and forms no part of the claimed design.

1 Claim, 4 Drawing Sheets
